UNITED STATES PATENT OFFICE.

JULIA M. HOLLISTER, OF DES MOINES, IOWA.

DESIGN FOR A TOY CHAIR.

56,159.

Specification for Design.

Patented Aug. 24, 1920.

Application filed April 27, 1920. Serial No. 377,122. Term of patent 7 years.

To all whom it may concern:

Be it known that I, JULIA M. HOLLISTER, a citizen of the United States, and a resident of Des Moines, in the county of Polk and State of Iowa, have invented a certain new, original, and ornamental Design for a Toy Chair, of which the following is a specification, reference being had to the accompanying drawing, forming part thereof.

Figure 1 is a front elevation.

Fig. 2 is a side elevation; and
Fig. 3 is a rear elevation, showing my new
and ornamental design for a toy chair.

I claim:

The ornamental design for a toy chair,
as shown.

Des Moines, Iowa, April 5, 1920.

JULIA M. HOLLISTER.
